UNITED STATES PATENT OFFICE.

HERMAN E. VANCE, OF COLUMBUS, OHIO.

FIREPROOF WINDOW-FRAME.

982,317.

Specification of Letters Patent. Patented Jan. 24, 1911.

Application filed April 27, 1908. Serial No. 429,345.

To all whom it may concern:

Be it known that I, HERMAN E. VANCE, a citizen of the United States, residing at Columbus, in the county of Franklin and State of Ohio, have invented a certain new and useful Improvement in Fireproof Window-Frames, of which the following is a specification.

The primary object of this invention is to provide a simple, cheap and practically in-
10 combustible sash for closing a window open-
ing; but the invention is available in the
manufacture of other glazed structures, as
for example, glass doors.

The invention consists in the construction
15 and combination of parts hereinafter set
forth and claimed, the invention not being
confined in its application to the form shown.

In the accompanying drawings—Figure 1
is a perspective view of fractions of upper
20 and lower portions of a window sash; Fig.
2 is a sectional view illustrating one method
of connecting the pane with the sash mem-
ber; Fig. 3 is a similar view showing a modi-
fication of the mode of uniting the pane with
25 the sash member.

As exemplified in the upper portion of
Fig. 1, the sash members are each preferably
made of three strips of sheet metal 5, 6, and
7, suitably bent and shaped, the pieces 5 and
30 6 being bent or rolled to form lips 5^a and 6^a
between which the wire edge of the glass
pane is inserted, walls 5^b and 6^b offset from
the lips to form a groove for the body proper
of the pane, and hook members 5^c and 6^c to
35 be engaged by hook members 7^a and 7^b of
the sliding member 7. The sash member
shown in the lower portion of Fig. 1 is a
modification of the form shown in the upper
portion of that view.

40 Generally the pane is united to the sash
members by inserting the selvage between
the lips 5^a and 6^a of the sash members and
then riveting the lips together. The con-
nection can be made in a number of ways,
45 two of which are illustrated in Figs. 2 and
3. In Fig. 2 the rivets 10 are passed
through the figure of the mesh at the sel-
vage. In Fig. 3, which shows a greater
extension of the selvage, the wire is shown
50 as bent over one of the lips for the purpose
of anchoring the pane. In this case the
rivets need not be passed through the figure

of the mesh of the selvage. It may in
this case be passed between the figures, the
rivets serving merely to unite the lips. 55
After the pane has been riveted in place in
the inner parts 5 and 6 of a sash member
the part 7, which can be slid into place, is
inserted, as shown.

While I, at present, propose to connect 60
all four of the edges of the pane with the
sash members it is obvious that this need
not necessarily be done. For example, the
pane can be anchored, as described, at the
upper edge only so as to be suspended and 65
therefore prevented from collapsing or fall-
ing down when softened by high heat.

Materials other than metal might be used
in the sash members.

What I claim and desire to secure by Let- 70
ters Patent is:

1. In a glazed structure, the combination
of a hollow sheet metal frame open at one
side and having parallel portions bent at
angles toward each other to form confining 75
seats for the faces near the edge and the
edge of a wire glass pane, and anchoring
lips bent outward from and at angles to
said edge seat, said pane provided with wire
selvage, the said selvage extended between 80
said lips, means for securing said lips and
selvage together and a sheet metal portion
for closing said hollow frame after the sel-
vage has been secured thereto, substantially
as described. 85

2. In a glazed structure, the combination
of a hollow sheet metal frame open at one
side and provided with grooves for the re-
ception of a sliding closing member, and
said frame having parallel portions bent 90
at angles toward each other to form con-
fining seats for the faces near the edge and
the edge of a wire glass pane, and anchoring
lips bent outward from and at angles to
said edge seat, said pane provided with 95
selvage, the said selvage extended between
said lips, means for securing said lips and
selvage together and a sheet metal portion
to enter the aforesaid grooves for closing
said hollow frame after the selvage has been 100
secured thereto, substantially as described.

HERMAN E. VANCE.
